CLAIM

The ornamental design for a combined lamp and planter, substantially as shown and described.

DESCRIPTION

FIG. 1 is a perspective view of a combined lamp and planter illustrating our new design;

FIG. 2 is a side elevational view thereof;

FIG. 3 is an end elevational view thereof; and

FIG. 4 is a plan view thereof.

The plant and the grommet and the wire are shown in broken lines for illustrative purposes only.

FIG. 1

FIG. 3

FIG. 4

FIG. 2
